UNITED STATES PATENT OFFICE.

HARRY F. SMITH, OF DAYTON, OHIO, ASSIGNOR TO THE GAS RESEARCH COMPANY, OF DAYTON, OHIO, A CORPORATION OF OHIO.

ENGINE MOUNTING.

Application filed May 11, 1922. Serial No. 560,079.

This invention relates to certain improvements in engine construction, and more particularly to certain improvements in the mounting of an engine.

5 While this invention is applicable to any type of engine, it is, perhaps, peculiarly adaptable to an internal combustion engine, comprising one element of a power generating set, such as a combined gas engine and electric generator. Whereas it has been the practice in the automobile industry, both with passenger cars and with trucks, to use a high speed internal combustion engine which is of comparatively light weight per 10 horsepower; it has been, on the contrary, the very general practice, in stationary power plants, to use internal combustion engines of comparatively slow speed and, therefore, of considerably greater weight per horsepower. The engines forming elements of such stationary power plants have been, therefore, as a general rule, large and comparatively cumbersome, and of a speed, ranging from perhaps 300 R. P. M. in engines of 25 horsepower, down to slower speeds, depending on the size; as compared with speeds of 900 R. P. M. up to 1200 to 1500 R. P. M. in the automobile type engine. Slow speed stationary engines, of the kind heretofore generally used, are generally arranged so that the infrequent adjustments of the crank shaft bearings, the connecting rod bearings, etc., may be taken care of by removing cover plates, and the like, giving access to these parts. But in the lighter, high speed engines of the automobile type this cannot ordinarily be done, for such engines are designed, generally, with the lower portion of the crank case removable to give access to the crank shaft, the connecting rods, the pistons, and cooperating parts. This is a generally satisfactory arrangement where the engine is mounted as in a truck, for it is readily accessible from beneath. Where 15 an engine of this sort, however, is used as the power generating element of a stationary power plant, it is mounted upon a stationary base plate, or other similar supporting member, and therefore the removal of the lower half of the crank case may not be easily effected without tearing down the whole engine mounting, and even if the lower half of the crank case could be easily removed ready access to the crank shaft, connecting rods and bearings would not nec-

essarily follow. This is quite objectionable and the principal object of this invention is to so construct an engine, of this character, and its associated piping and the like, and to so mount that engine with relation to the base upon which it is supported, that ready access may be had to the crank shaft, connecting rods and the like with the minimum of effort and with the disturbance of a very small number of parts.

65 Other objects, and advantages will be apparent from the description thereof, set out below, when taken in connection with the accompanying drawings.

In the drawing, in which like characters 70 of reference designate like parts through the several views thereof;

Fig. 1 is a side, elevational, view of an engine of the character described, with certain parts thereof broken away and shown in section, to more clearly illustrate the invention;

75 Fig. 2 is an elevational view at right angles to the view shown in Fig. 1, looking in the direction of the arrows, with the engine in the normal position, that is the position occupied during regular operation of the engine;

80 Fig. 3 is a view corresponding to Fig. 2, but with the engine shown as positioned for giving access to the crank case, the crank shaft, connecting rods, etc., associated therewith;

85 Fig. 4 is a view similar to Fig. 2, but looking at the engine from the opposite end, part of the mechanism being shown in section in order to more clearly disclose the invention thereof; and

90 Fig. 5 is a fragmentary sectional view showing, in detail, a coupling within the exhaust pipe.

95 As stated above this invention is applicable to any type of engine, but it is obviously more readily applicable to engines of comparatively small size than to the big and massive engine constructions which are incorporated in those engines of bigger size, say several hundred horsepower up; although the invention may be applied to any type of engine, regardless of its size. For purposes of description, however, and as illustrating 100 a preferred embodiment of the invention, the engine shown is a four cylinder internal combustion engine, of a type quite widely used in automobile trucks, this engine being designated generally by the nu- 105

meral 10. Since the specific construction of the details of the engine, such as the pistons, connecting rods, and crank shaft arrangement, the valves and operating mechanism therefor, and the like, is of no particular importance so far as this invention is concerned, the engine is shown somewhat diagrammatically, and very largely in outline. This particular engine however is of 10 the four cylinder type, and is provided with an inlet pipe and manifold 11, an exhaust manifold and pipe 12, a gas supply pipe 13, through which gaseous fuel, such as natural gas, producer gas, or the like is introduced 15 to a mixing valve 14, which may be of any conventional construction and which functions in place of the carburetor ordinarily used with liquid fuels, air being admitted through the pipe 15, the resulting combustible mixture passing into the cylinders in the desired way, through the inlet manifold 11, to cause operation of the engine. The pipe 15 also serves as a priming pipe for starting the engine, where it is operating upon gas, gasoline or other suitable 25 priming fluid being introduced therewith for starting so that a mixture of air and priming fluid is drawn in through the mixing valve 11 which is so constructed 30 that the fuel supply pipe 13 may be entirely disconnected from the inlet manifold or partly connected thereto at the same time that the pipe 15 is connected thereto. Of course where it is desired to operate continuously upon a liquid fuel such as gasoline, a suitable carburetor should be used in 35 place of the mixing valve. This inlet pipe 13 is provided with a conventional sleeve union 20, the details of construction of 40 which are not shown since it may be of any desired character so long as it is readily detachable. As shown proper manipulation of the union sleeve will either entirely disconnect the two sections of the pipe 13, or 45 will cause them to be connected together with a tight joint.

The type of engine shown is of the water cooled variety the cylinders being provided with the conventional water jackets, water 50 being introduced to these jackets, in the arrangement shown, through the pipe 25 from any suitable source of supply. The pipe 25 opens into the pipe 26, one end of which is connected to the water manifold 27, which 55 opens into the top of the water jacket of the various cylinders, while the other end is connected through the pipe 28 to the lower end of the water jacket of the cylinder block. Leading off from the pipe 26 is the overflow pipe 29, the free end of which is positioned to empty into the discharge pipe 30. The construction just described may be used, 60 where there is an abundant supply of water for cooling purposes, in place of the conventional radiator. In this construction the

valve 31, which controls the flow of water through the pipe 25 is set to permit the flow of a predetermined quantity of water through the pipe 25 into the cooling system of the engine, the usual pump, not shown 70 since it is of any conventional character and is operated in the conventional manner, causing circulation of the water within the cooling system, the excess water, resulting from the continuous introduction of cooling water 75 through the pipe 25 escaping from the system through the pipe 29 into the discharge pipe 30. By properly manipulating the valve 31 the quantity of water which is continuously added to the cooling system may 80 be so regulated as to give any desired cooling effect. Where a radiator is used this part of the system can be entirely dispensed with, the radiator being connected to the top and bottom of the cylinder jacket, as is the 85 conventional practice, the heated water being circulated from the jacket to the radiator where it is cooled and then caused to flow back into the jacket. The pipe 25 is provided with a detachable coupling 32, which 90 is shown, diagrammatically, as of the conventional sleeve union type, so that the two sections thereof may be readily disconnected to disconnect the engine from the main portion of the pipe 25. And where a radiator 95 is used there should, preferably, be a detachable coupling in each of the pipes connecting the radiator to the water jacket of the engine; though if desired the radiator may be attached so as to move with the 100 engine as it is rolled over.

The engine may be supported in any suitable manner but it is preferably mounted upon a bed or base plate 40 which is shown upon a bed or base plate 40 which is shown 105 as a rectangular cast iron member having an upstanding standard 41, attached to the base member, at one end thereof by any suitable means, the means being shown as bolts of conventional character. This standard is adapted to support the front end of the 110 engine, and is provided with a passage 42 therein, which, when the engine is in assembled position, receives the extension or projection 43, carried by the engine, and preferably substantially coaxial with the 115 crank shaft of the engine. As shown this extension 43 is connected to the engine by means of a base 44, which cooperates with the correspondingly shaped face upon the engine and is held tightly connected thereto by means of stud bolts 45. A set screw 46 is so mounted within a threaded passage in the standard 41 that its end may be forced into contact with the member 43 to lock that member and the standard 41 against 120 movement relative to each other.

The rear end of the engine has attached thereto a circular ring, or detachable flange, 50, which is rigidly secured to the engine by means of the bolts 51, as shown particu- 125 130

larly in Fig. 4. If desired the ring 50 may be made integral with the engine body. Rigidly secured to the base member or bed plate 40 is a ring 55, having an inturned flange 56, which is adapted to fit over and snugly receive the extension 52 of the ring or flange 50, the construction being such that the two members may be rotated relatively to each other. The ring 55 may be supported by and secured to the bed plate 40 in any desired manner, but, as shown most clearly in Fig. 4 it is thus secured in place by means of extensions 57, formed integrally therewith, and adapted to seat upon the bed plate, suitable bolts 58 passing through these extensions 57 and being threadedly engaged within suitable threaded openings in the base member to hold the two rigidly connected. The circular flange 50, and the ring 55 are so constructed and arranged that they are positioned coaxially with each other, and also with the extension 43 at the front end of the engine, and with the crank shaft one end of which is shown, in Fig. 1, as designated by the numeral 59.

This construction is such that the engine may be thus readily rotated about the axis of the extension 43 and of the members 50 and 55, provided the water supply pipe, fuel supply pipe, and the like, are not so connected as to prevent such rotation. However, as shown in Figs. 2 and 4 the normal position of the engine during operation, is substantially vertical. And the water supply pipe, the fuel supply pipe, and the exhaust pipe, are all so arranged that when they are connected up for operation of the engine, the engine is in this normally vertical position. Furthermore the set screw 46 is provided so that the extension 43 may be clamped against rotation. Also the ring 55 is provided with two bolts 65, which extend therethrough, and are threadedly engaged in suitable openings 66, within the circular flange 50, this arrangement being such that when these bolts are positioned within the passage 66, the flange 50 and the circular ring 55 are held against movement relative to each other. And inasmuch as the ring 55 is in turn rigidly secured to the bed plate the engine is positively maintained in normally vertical operating condition. The ring 55 is preferably provided with a cover plate 70, which is held in position by means of the bolts 65, and also by means of the supplementary stud bolts 71, which are threaded into sockets within suitable lugs carried by the ring 55.

The engine, is shown, as adapted for driving an electrical generator, the armature of the generator being mounted upon the shaft 75, which constitutes, in effect, an extension of the crank shaft 59. The shaft 75 is in driving connection with the crank shaft through a flexible coupling which connects

it to the fly wheel 76, mounted upon the crank shaft. Any suitable type of flexible coupling may be used, but the coupling shown consists of two pins 77 carried by the fly wheel, which, when the device is assembled, are positioned within corresponding sockets in the flange member 78, which is mounted upon the shaft 75. The pins 77, where they extend into the sockets in the flange 78, are preferably surrounded with sleeves of leather thus giving a flexible coupling. But, as stated, any other satisfactory type of commercially known flexible coupling may be used. If desired the shaft 75 may carry a pulley, instead of the armature of a generator, adapted to receive a belt or a chain through which the power of the engine may be transmitted for doing useful work. The axis of the extension 43, the flange 50 and the crank shaft 75 are preferably coincident so that the engine may be rolled over in its supports without disturbing the generator or other apparatus connected to the crank shaft.

The exhaust pipe 12, as shown particularly in Figs. 2, 3 and 5 is not provided with a detachable coupling of such character as is shown in the fuel supply pipe and the water supply pipe. Since it is not necessary to secure such a leakless connection in this pipe as is the case with the fuel supply pipe and the water supply pipe, the pipe is merely arranged so that when the engine is in normally operative position the portion of the pipe which is rigidly secured to the engine will abut against the free end of that portion of the pipe which is attached to the bed plate a suitable gasket being held between the abutting ends of the two sections of the pipe to prevent undesirable escape of exhaust gases through the joint. As shown particularly in Fig. 5 that portion of the exhaust pipe which is rigidly connected to the engine is provided with an internally threaded socket 80 in which is threadedly mounted a sleeve 81 having a flange or abutment member 82 upon the end thereof. That portion of the pipe which is rigidly secured to the bed plate, and which cooperates with the flanged end 81, is also provided with a flange or abutment member 83. By means of this construction, when the engine is in vertical position, and the two flanges 82 and 83 are then in close juxtaposition, a sufficiently tight joint may be secured by manipulating the threaded sleeve 81 to bring those two flanges closer together, and to cause them to clamp a gasket 84, which may be of asbestos or other suitable material, sufficiently tight to prevent leakage therethrough. This construction is such that it is not necessary in breaking this joint, in order to rotate the engine about the axis of the extensions 43, and the rings 50 and 55, to manipulate a detachable coupling since upon such rotation

of the engine the two sections of the exhaust pipe will merely separate. Since a tight joint is necessary in both the water supply pipe and the fuel supply pipe however, it is necessary that some type of readily detachable coupling be employed.

From the construction shown, it is evident that in order to swing the engine about its axis it is only necessary to disconnect the joint 20 in the fuel supply pipe and the joint 32 in the water supply pipe, run back the bolts 65 so that the flange 50 and the ring 55 are not rigidly connected together and then move the engine, the extension 43 turning within the passage 42 of the standard 41, and the flange 50 turning within the cooperating flange 56 of the ring 55.

This engine, like other engines of similar character, has a detachable cover 90, for 20 the crank case, access to the crank shaft, the connecting rods, the various bearings, the pistons etc. being had by removing this cover 90. As clearly shown in the drawing, with the engine positioned for operation, 25 the cover 90 may not be removed and even if it were this would not give ready access to the connecting rods and the like. Heretofore it has been necessary, with engines of this character, to completely dismantle the 30 engine, remove it from its base, and jack it up in order to gain access to the crank case. With the type of construction described above the connection between each end of the engine and its cooperating supporting 35 means constitutes in effect a swivel connection, and it is merely necessary to disconnect the detachable coupling in the water pipe, the detachable coupling in the fuel supply pipe, run back the set screw 46, and 40 remove the two bolts 65, in order to freely swing the engine about the axis of its supporting members to bring the crank case, and its cover 90, into readily accessible position. As shown in Fig. 3 when the engine is 45 thus swung about its supports or rolled over it is preferably moved into a position substantially 90° from its normal position, that is with the engine in a substantially horizontal rather than a substantially vertical position, but it may be caused to assume any other suitable position. And as is 50 evident from Fig. 3 when in this position it is a very simple matter to remove the cover plate 90 and gain ready access to the crank 55 case and the parts therein.

As shown most clearly in Figs. 2, 3, and 4, the ring 55 is provided with two spaced stops 100 and 101 which are positioned substantially 90° apart, and the circular flange 60 50 is provided with a lug 102, so positioned that as the engine is rotated about its axis this lug will be brought into contact with one or the other of the stops 100—101. These stops are so positioned that the lug 65 102 will contact with the stop 101 when the

engine is in substantially vertical position and will contact with the stop 100 when the engine is in substantially horizontal position. Not only does the stop 101 serve to limit the movement of the engine as it is 70 swung or rolled over upon the supports, but it also serves to take the engine torque, during operation, and thus relieve the strain upon the bolts 65.

While the form of apparatus herein described constitutes a preferred embodiment of the invention, it is to be understood that the invention is not limited to this precise form of apparatus, and that changes may be made therein without departing from the 80 scope of the invention which is defined in the appended claims.

What is claimed is:

1. In a vertical engine, having a crank shaft, a connecting rod, and bearings therefor; an extension mounted at one end of said engine, supporting means for said extension comprising a bearing adapted to rotatably receive the said extension; a circular flange mounted upon the other end of said engine, and supporting means for said circular flange comprising a cylindrical sleeve adapted to rotatably receive said circular flange, the construction being such that the engine may be swung, within the said supporting means, into a substantially vertical or substantially horizontal position.

2. In a vertical internal combustion engine, and in combination; a base plate for said engine; a supporting member, carried by said base plate, comprising a bearing constructed to rotatably receive an extension carried by the said engine, a second supporting member mounted upon said base plate, comprising a cylindrical bearing sleeve constructed for rotatably receiving a cooperating circular flange carried by said engine, and means for locking said cylindrical sleeve and circular flange against rotation relative to each other, said means comprising a bolt carried by the said cylindrical sleeve, and a threaded socket within said circular flange adapted to receive said bolt.

3. In a vertical engine having a crank shaft, connecting rod, bearings, and the like, therefor, and in combination; an extension mounted at one end of said engine, supporting means for said extension comprising a bearing adapted to rotatably receive said extension; a circular flange, mounted on the other end of said engine, and supporting means for said circular flange comprising a cylindrical sleeve adapted to rotatably receive said circular flange; the said extension with its bearing, and the said circular flange with its cooperating cylindrical sleeve, being substantially coaxial with the normal axis of the crank shaft; the construction being such that the engine may be rolled about the said normal axis of the crank shaft.

4. In a vertical engine, which engine comprises means for supporting it, constructed for permitting rolling over of said engine about said supporting means, and a fuel supply pipe having a detachable connection therein so that the sections of such fuel supply pipe may be readily disconnected to permit rolling over of said engine; an exhaust pipe comprising two sections, one carried by the portion of the engine which is adapted for rolling over, and movable with said portion, the other section being sepa-
rate from the portion of the engine which may be rolled over and held stationary during such rolling over, and abutting members 15 on the cooperating ends of the two sections of said exhaust pipe constructed to contact to form a suitable tight joint for the exhaust pipe when the engine is in normal position, and to readily separate when the engine is rolled over.

In testimony whereof I hereto affix my signature.

HARRY F. SMITH.
